UNITED STATES PATENT OFFICE

2,185,867

TOOTH BRUSH HEAD

Irving Pensky, Brooklyn, N. Y.

Application August 18, 1938, Serial No. 225,561

1 Claim. (CL. 306—6)

This invention relates to new and useful improvements in tooth brushes and more particularly it pertains to a tooth brush head for use in connection with handles such as illustrated in 5 my prior patent, No. 2,114,149, of April 12, 1938.

It is the primary object of the present invention to provide a new and novel construction of tooth brush head which may be detachably connected to a handle of the type shown in my prior 10 patent, above mentioned.

It is a further object of the invention so to construct the tooth brush head that it may be firmly gripped and held in either a position at right angles to the axis of the handle, or in a 15 position in alignment with said axis as may be desired.

With the above and other objects in view, reference will be had to the accompanying drawing and the following specification and claim.

20 In the drawing:

Figure 1 is a perspective view of my new and improved brush head.

Figure 2 is a view in elevation, illustrating my brush head secured to a handle such as shown 25 in my patent heretofore mentioned, the brush head in this figure being positioned at right angles to the longitudinal axis of the handle.

Figure 3 is a fragmentary plan view illustrating 30 my improved brush head secured to the handle in alignment with the longitudinal axis thereof, and.

Figure 4 is a fragmentary view, partly in section, the section being taken substantially on the line 4—4 of Figure 3.

35 Referring to the drawing by reference character, 10 designates a brush head constructed in accordance with the present invention. The brush head comprises a main body portion 11, from one side face of which the bristles 12 are mounted. The main body portion 11 and the bristles 12 form no particular part of the present invention and may be of any desired shape, size or form.

Extending from the main body portion 11 of 45 the head and preferably from one end thereof, there is a relatively short extension 13. This extension 13 has a contracted neck portion 14 which is positioned between the end of the extension and the main body portion 11. The free extremity of the extension 13 ends abruptly in a flat rectangular wall 15 and within the confines of the extension, there is a transversely extending opening 16. This opening is of rectangular form and the specific purpose thereof will be hereinafter 50 set forth.

The handle, which is designated 18 in the drawing, has a slideable member 19 operated by a nut 20. This slideable member 19 has a beveled end

face 21 which cooperates with a nose portion 22 which is angularly disposed upon a body portion 23 which in turn constitutes an extension of the two arms 24.

When it is desired to position the brush head so that its longitudinal axis extends at right angles to that of the handle 18, the contracted neck portion 14 of the brush head is placed between the beveled end face 21 of the sliding member 19 and the nose portion 22 of the body portion 23 10 after which the sliding member 19 is moved by the nut 20 into clamping engagement with the contracted neck portion 14 of the brush head to clamp and hold the same in operative position as shown in Figure 2.

With the head in this position with relation to the brush, a straight up and down movement of the brush bristles in a direction lengthwise of the teeth, this being the most effective way to clean them, and this can be effected without 20 discomfort on the part of the user since he may perform the operation with his arm close to the body instead of in the extremely awkward position required of the arm to perform this operation with a brush of usual type.

When it is desired to secure the brush head in alignment with the longitudinal axis of the handle member as illustrated in Figures 3 and 4, the nose portion 22 is inserted into the opening 16 and the angular face 20 of the movable member 19 moved by the nut into engagement with the edge 30 of the flat rectangular wall of the extension 13 of the brush head.

In this last described position, the brush head is firmly clamped in alignment with the longitudinal axis of the handle member and the device is employed as an ordinary tooth brush.

From the foregoing, it will be apparent that the present invention provides a new and novel tooth brush head which may be used in connection with handles by which it may be removably carried, and more particularly the invention provides a brush head which is especially adapted for use with the handle illustrated in my aforementioned patent.

Having thus described the invention, what is claimed, is:

A brush head of the type described comprising a relatively thin body portion, a relatively short extension projecting from one end thereof and terminating in a flat rectangular end face having a definite upper outer edge, a contracted neck portion separating said extension from the main body portion, and an elongated opening extending transversely of said relatively short extension between the contracted neck portion and the free end of the extension.

IRVING PENSKY.
